UNITED STATES PATENT OFFICE.

ARTHUR A. SCHUMACHER, OF NORWOOD, OHIO.

DEVICE FOR CLEANING PIPES OF CORROSION SEDIMENTS AND THE LIKE.

1,135,058.

Specification of Letters Patent. Patented Apr. 13, 1915.

Application filed April 11, 1914. Serial No. 831,831.

To all whom it may concern:

Be it known that I, ARTHUR A. SCHUMACHER, a citizen of the United States, and a resident of Norwood, in the county of 5 Hamilton and State of Ohio, have invented certain new and useful Improvements in Devices for Cleaning Pipes of Corrosive Sediments and the like.

This invention relates to devices for facilitating the cleaning of water pipes and more particularly coils, and manifolds of all corrosive sediments, etc., without dismantling the pipes, coils, or manifolds, and, if an automatic heater is used, without dismantling the heater.

In localities where hard water is used the water pipes often become clogged due to corrosion or precipitation caused by the ingredients of the hard water. This is particularly true when water is heated, especially in the well known form of automatic heaters.

The object of this invention is to provide a device for permanent installment in one of the pipes of the water heater, which, after the heater or receptacle containing the water to be heated is drained of all water, can be filled with acid such as hydrochloric acid or the like, and thereby feed same into the pipe of the heater or receptacle, after which the water pressure may be gradually turned on to force the acid or other agents through the pipe, thereby cleaning them of sediments, or corrosive substances.

Another object of this invention is to provide a device of the character described which is constructed so as to form an air cushion to counteract any hammering in the pipes due to the sudden shutting off of the flow of water therethrough.

The invention consists in constructing and installing a substantially L shaped tank or receptacle, which is adapted to receive a pipe at the top and bottom of the horizontal portion, the vertical portion having an inlet at the top thereof, and the walls of the entire device tapering toward the outlet pipe forming a natural drain for the contents of said receptacle, through one 50 one of the pipes connected thereto.

In the accompanying sheet of drawing which serves to illustrate my invention and which shows a preferred construction: Fig-

ure 1 shows my improved device connected to the vertical supply pipe of an automatic water heater. Fig. 2 is an elevation of the device. Fig. 3 is a central vertical section taken through my improved device.

Referring more particularly to the drawing, 1 illustrates an automatic water heater 60 and 2 the inlet or supply pipe thereof, and 3 the outlet pipe. Mounted in the supply 2 I provide my improved cleaning apparatus 4 which consists of the L shaped casing 5 having a vertical portion 6 and a horizontal 65 portion 7. At the top of the vertical portion 6 I provide a removable plug 8.

The pipe 2 is divided at its point of connection with the improved cleaning device 70 4, and is connected to the horizontal portion 7 as indicated at 9 and 10.

It will be noted that the pipe 10 forms a thorough drain for the receptacle which is necessary in this device in order to insure to the user that no poisonous acid has been 75 allowed to remain in the tank. The inner walls of the receptacle 4 are all shaped so as to cause the contents of the receptacle to flow toward the outlet 10.

This device is intended for permanent installment and can be brought into use at any time desired.

The operation of the cleaning of the pipes is substantially as follows: The water pressure is first turned off, and then the valve 85 15 which is in the supply pipe for the heater is opened and the pipes in the heater are thoroughly drained. The valve 15 is then closed and the plug 8 removed from the vertical portion or neck 6 of the device. The 90 receptacle 4 is then filled with hydrochloric acid. This acid runs down through the pipe 2 to the heater coils and may be forced therethrough by gradually turning on the water pressure again, thereby causing the 95 acid to eat its way through the pipes of the heater and to clear them of all corrosive sediments and the like.

Modifications of my invention may be made without departing from its spirit and 100 scope and I do not wish to be confined to the exact details shown.

What I claim as new and desire to secure by Letters Patent is:

The combination with a water heater having an inlet and outlet pipe, of a receptacle

permanently connected to one of said pipes, said receptacle substantially L shaped in construction, the horizontal portion thereof being connected at the top and bottom to one of said pipes, and means for closing the opening at the top of said vertical portion.

In testimony that I claim the foregoing

I have hereunto set my hand in the presence of two witnesses.

ARTHUR A. SCHUMACHER.
